W.G. Foglesong
Carriage Top.
No. 12,751 Patented Apr. 17, 1855.

UNITED STATES PATENT OFFICE.

WILLIAM G. FOGLESONG, OF XENIA, OHIO, ASSIGNOR TO FOGLESONG & ANDERSON.

FOLDING TOP FOR CARRIAGES.

Specification of Letters Patent No. 12,751, dated April 17, 1855.

To all whom it may concern:

Be it known that I, WILLIAM G. FOGLESONG, of Xenia, in the county of Greene and State of Ohio, have invented a new and Improved Frame for Carriage-Tops; and I do hereby declare the following to be a full, clear, and exact description thereof, reference being had to the annexed drawings, making part of this specification, and in 10 which a buggy-top constructed on my plan is represented by side elevation.

The object of my invention is to provide a means of spreading stretching and folding the top of a buggy, which shall be simpler in construction, more elegant in appearance, less costly and more easily operated, than are the unsightly and inconvenient stretchers or elbows now in use.

The object I accomplish by means of a 20 pair of triggers like the one represented at (a) pivoted to the front edges of the principal bow or slat iron (b), a little above its hinged junction to each respective stem (c). This trigger is provided at its lower 25 end with a catch pin (d) which engaging within a suitable socket in the front of the stem below the hinge (f) holds the principal bow (b) and those (g, h) behind it to their opened or spread position. A 30 spring (j) causes the catch pin (d) to engage automatically within its socket, the instant that the bow is brought forward to a line with the stem. All therefore that is

required to be done, in order to fix the hood permanently open, is merely to press forward the principal bow until the catch pin engages; and in order to lower the hood, you have only to press a hand on each trigger, and thus allow the frame to collapse of its own weight. This movement can be 40 effected without rising or turning around in the seat.

A small stretcher (k) inside of the frame may be employed to hold forward the front bow. No other stretcher or elbow will be 45 required thus effecting a saving of from three to twenty dollars in the original outlay, and greater durability of top, because the wear of the quarter leather by the abrasion of the stretcher is done away with. 50 The top, has moreover a much neater appearance.

I claim herein as new and of my invention—

The application of a catch (a) as described, or its equivalent, in front of the hinge which unites the principal bow or slat iron to the stem; for the convenient stretching, &c., of a carriage or buggy top 55 as explained.

In testimony whereof, I hereunto set my hand before two subscribing witnesses.

WILLIAM G. FOGLESONG.
